DEVICE FOR PEELING POTATOES AND THE
LIKE

Cornelius Vernon McCauley, Waverley, Mass.

Application June 5, 1939, Serial No. 277,346

25 Claims. (Cl. 146—43)

My present invention relates to novel apparatus for use in removing surface layers from objects.

While my apparatus is adapted for use in treating the surface of many different types of objects, the many novel features and advantages of my invention may be best appreciated by considering its use in removing the skins of potatoes or in removing a uniform layer from other irregularly shaped objects.

The accurate and quick manual removal of the skins of certain vegetables, particularly potatoes, is difficult and while several devices have been proposed to facilitate such surface treatment, these have not been adapted to remove uniform layers from objects of different sizes and shapes.

In accordance with my present invention, I provide for the progressive rotative treatment of the surface of an object by which the cutting means may advance as required by the shape and size of the object rather than at the rate of predetermined relative movement between the object and the support for the cutting means. I am thus able to remove a surface layer of uniform characteristics from objects of different sizes and shapes and permits durable and efficient apparatus to be made by which objects may be treated with accuracy and rapidity.

In the drawings, I have shown an embodiment of my invention from which and the accompanying specification, its many novel features and advantages may be readily understood.

In the drawings:

Fig. 1 is a top plan view of an embodiment of my invention with the carrier for the cutting means in one extreme position.

Fig. 2 is a longitudinal section along the lines 2—2, of Fig. 1.

Fig. 3 is a fragmentary top plan view of the device shown in Fig. 1, but with the carrier in the other extreme position.

Fig. 4 is a longitudinal section through the device along the lines 4—4, of Fig. 3.

Fig. 5 is a cross sectional view through the device along the lines 5—5, of Fig. 4.

Fig. 6 is a similar view along the lines 6—6, of Fig. 4.

Fig. 7 is a fragmentary plan view of the device with the carrier in an intermediate position.

Fig. 8 is a plan view of one of the cutting members and its support.

Fig. 9 is a section along the lines 9—9 of Fig. 8, and

Fig. 10 is a view of another cutting member.

In order to facilitate the understanding of my

invention, I have undertaken first to describe the general construction of my device including the driving mechanism for the object support and the carrier for the cutting members. The cutting members and the means connecting them to the carrier are next described together with the cams and stops that cooperate to control their movement. By way of summary, I then present a discussion of the operation of my invention.

10 *General construction*

In accordance with my invention, I employ a frame 1 having a rear wall 2, the front of which supports a channel 3 to slidably support the carrier 4.

The back of the rear wall 2 is formed to present a pair of flanges 5 and 6. An adjustable member 7 is threaded through the lower flange 6 to permit the device to be securely clamped to any desired support.

A spindle shaft 8 having an object piercing and supporting head 9 is mounted as at 10 on the frame 1. The end of the shaft 8 carries a gear 11 in mesh with the driving gear 12 on the shaft 13 mounted as at 14 on the frame 1. While the shaft 13 may be rotated in any desired way, I have shown, for convenience, a crank handle 15 on the shaft 13.

An arm 16 is pivotally connected as at 17 to the carrier 4. An elongated gear or toothed member 18 is rigidly mounted on the arm 16 and is in mesh with a driving gear 19 on the shaft 13.

In order that the gears 18 and 19 may remain in mesh at all times, the end of the rear wall 2 is formed with a pair of vertically spaced guides 20 that maintain the gear 18 in mesh with the gear 19 as the gear 18 travels from one extreme position to the other. The end of the rear wall 2 is formed with an arcuate guide portion 21 adapted to be contacted by the pin 22 extending rearwardly of the arm 16 and to maintain the gear 18 in mesh with the gear 19 at one extreme end of the movement of the carrier 4 as is shown in Fig. 4. A similar but oppositely disposed arcuate guide 23 is carried by the shaft support 14 to be engaged by the pin 24 on the gear member 18 to maintain the gears 18 and 19 in mesh at the other extreme position of the carrier as is shown in Fig. 2.

The gear ratios employed are selected to establish a predetermined ratio between rotation of the spindle 8 and the movement of the carrier 4 from one extreme position to the other. While other actuating means may be employed, I prefer the mechanism just described because of its

simplicity and durability and because it permits the direction of rotation of the shaft 13 to be reversed at any time without any possibility of injury to my device or any of its parts.

At 25 I have shown a manually operable lever pivotally mounted on the flange 6 and under the influence of a spring 26 urging it to the position shown in Fig. 1. As shown in Figs. 3 and 5, the lever 25 is formed to be adjacent the spindle 8 so that the lever 25 may be employed to dislodge an object positioned on the object supporting means, i. e., the spindle 8 and the head 9.

The cutting means

In accordance with my invention I employ a pair of cutting knives 30 and 31. The knives 30 and 31 are pivotally mounted on loops 32 having end portions 33. The knives 30 and 31 are pivotally supported in the upturned portions of the arms 34 and 35, respectively, which are bored as at 36 to receive the portions 33 of the loops 32 or other structure that may be employed to pivotally mount the knives 30 and 31 on the arms 34 and 35. Preferably, a spring clip 5 detachably holds the knives in place so that the knives may be quickly and easily removed and replaced when desired.

The arms 34 and 35 are provided with pivot portions 37 and 38, respectively, carried by the flanges 4^a and 4^b of the carrier 4. The portions 37 and 38 are under the control of springs 39 which resiliently urges the arms 34 and 35 towards the spindle 8 and towards each other. Preferably as shown in Fig. 6, the pivotal portions 37 and 38 are provided with a sleeve 40 resting on a fixed hub 40^a carried by the carrier 4. In order to reduce friction to a minimum, the point of bearing of the sleeves 40 and the hub 40^a is midway of the spring 39. By this construction, the springs 39 do not bind the pivotal portions 37 and 38.

The arm 34 includes a rearwardly extending portion 41 preferably carrying a cam contacting roller 42 and the arm 35 includes a rearwardly extending portion 43 carrying a similar cam contacting roller 44. A stop 45 (see Fig. 4) limits the inward pivoting of the arm 34 and a similar stop 46 is adapted to be engaged by the head 47 of the pivot portion 38 to limit the inward pivoting of the arm 35. By this construction, the arms 34 and 35 and the knives 30 and 31 are prevented from being carried by the spring 39 into contact with the spindle 8. For example, the stop 46 limits the inward pivoting of the arm 35 so that when the arm 35 is in its extreme inward position, the knife 31 travels closely adjacent the spindle 8 as shown in Fig. 1. The stop 45 similarly limits the inward pivoting of the arm 34 so that the extreme inward position of the arm 37 permits the knife 30 to move along an axial path as shown by its dotted line position in Fig. 7.

In order to facilitate the placing of an object such as the potato P on the spindle 8 or its removal therefrom, I provide means so that at either limit of the movement of the carrier 4, the arms 34 and 35 are positioned so that the knives 30 and 31 are remote from the object. I have shown at 48 a member including cam surfaces 48^a and 48^b secured to the top of the rear wall 2 adapted to be contacted by the roller 42.

As the carrier 4 moves from the extreme position shown in Fig. 3 to the position shown in Fig. 1, the inward pivoting of the arm 34 is first controlled by the stop 45 that permits the knife 30 to cut axially of the spindle 8 as shown by its

dotted line position in Fig. 7. When the knife 30 approaches the head 9, the cam portion 48^b is adapted to be contacted by the roller 42 to pivot the arm 34 against the action of the spring 5 39 to prevent the knife 30 from striking the head 9. The cam surface 48^a is adapted to be contacted by the roller 42 to pivot the arm 34 to carry the knife 30 into the inoperative position shown in Fig. 1. It should be noted that the cam surface 48^b is likewise effective to control the arm 34 if the knife 30 reaches the common position, a factor dependent on the particular object being treated.

A cam member 49 is mounted on the bottom of the rear wall 2 and includes cam surfaces 49^a and 49^b adapted to be contacted by the roller 44 to pivot the arm 35 against its spring 39 in much the same manner as the control of the arm 34 by the cam surfaces 48^a and 48^b. Thus, the cam portion 49^b controls the arm 35 to prevent contact of the knife 31 with the spindle head 9 and cooperates with the cam surface 49^a to move the knife 31 towards an inoperative position whenever it reaches the common position.

It will be noted from Fig. 1 that when the knife 30 is in an inoperative position, the knife 31 is adjacent the spindle 8, but sufficiently out of the way so that it may be considered in an inoperative position.

At 50 I have shown a trip carried by the wall 2 adapted to be contacted by the trip member 51 carried by the pivot portion 37 of the arm 34 as the carrier 4 approaches the position shown in Fig. 3 to pivot the arm 34 to carry the knife 30 into an inoperative position as the knife 31 is likewise moved into an inoperative position by the cam member 49.

Reference should now be made to the details of construction of the knives 30 and 31. It will be appreciated from the description of the apparatus just described that as the object is rotated, the knives 30 and 31 are advanced along the rotating object. Accordingly, the construction of the knives is of considerable importance in order that they may adjust themselves as required by the shape of the object. That is, since the object is rotating and the knives advancing relative to the object, the distance of the knives from the axis defined by the spindle 8 is constantly subject to variation. The knives 30 and 31 include a guard portion 52 and a blade portion 53 (see Figs. 8-10). Preferably both the guard 52 and the blade 53 are longitudinally arcuate, although either or both may be flat intermediate the ends. As shown in Fig. 9, the front edge of the guard 52 is upturned as at 54.

Preferably the guard 52 and the knife 53 are in substantially the same plane in order to minimize frictional drag. The aperture 55 between the edge of the knife portion 53 and the guard 52 is proportionate to the desired thickness of the surface layer to be removed.

The loop or like attaching member 32 is pivotally attached to the guard 52 adjacent the edge of the knife portion 53.

By this construction of the knives, the guard 52 and blade 53 are both in contact with the surface of the object and the pressure on both serves to keep the knives in proper cutting position at all times since they are free to pivot on the loops 32 and the loops are pivotally mounted in the arms permitting universal adjustment of the knives.

The knives 30 and 31 are substantially identical. The knife 31, however, may include a guide

portion 56 adapted to rest on the spindle 8 as shown most clearly in Fig. 10.

Operation

Before considering the operation of my device it will be found helpful if certain essential principles are kept in mind.

For example, it will be appreciated that in any device for use in removing a surface layer from objects of different sizes, the cutting members must be adjustable to permit objects of different sizes to be accommodated. This may be accomplished by a mounting of the cutting members on their support under the control of resilient means by which the resilient means always carry the cutting members into contact with the surface of the object to be treated.

Where, however, objects such as potatoes or the like are to be treated or where the surface of the object and the path of movement of the support for the cutting means present non-parallel lines, it will be appreciated that a different problem is presented. For example, the removal of a surface layer from a cylinder requires the same distance of relative linear movement of both the cutting means and the support and the surface of the object is parallel to the path of the support. By way of contrast, if the object to be treated is spherical, on a linear movement of the carrier equal to the radius of the object, and equal to the linear movement employed in treating the cylinder, the difference between the distance represented by the radius and the arc defined by an angle of 90° will be obvious. With such an object, the distance to be cut by a knife on a predetermined movement of the carrier is obviously much greater than the distance of travel of a knife on the same movement when a cylindrical object is to be treated. Thus it will be appreciated that whenever the path defined by the travel of a cutting member along the surface of a rotating object varies in its relation to the path of the carrier, the distance of travel of the cutting member is increased. In accordance with my invention, the cutting member lags behind the travel of the carrier in relation to the variation of its path.

For that reason, I mount each of the knives 30 and 31 on arms pivotally carried by the carrier 4 under the influence of springs 39 to pivot the arms 33 and 34 towards each other. Each of the arms 33 and 34 pivots through a plane to carry its knife through a plane substantially inclusive of the spindle 8. In order to simplify the construction of my invention, I have provided the above disclosed structure by which the knives 30 and 31 are pivotally carried through a common plane.

With this construction it is possible for a knife to travel along the surface of a rotating object in fixed relation to the carrier 4 as when the surface is cylindrical or to pivot closer to the spindle 8 or further away from the spindle 8 as required by the distance of the portion of the object to be treated from the spindle 8. While it is true that the movement of the carrier 4 always causes a like travel of the knives, unless the arms pivot, this movement of the knives, in terms of parallel travel, is less than the movement of the carrier 4 when the arms pivot nearer to or further away from the spindle 8. For that reason, it will be found convenient to consider the effect of the pivoting of the arms as resulting in a retarded advancement of the knives relative to the carrier 4, a condition that results

whenever the arms are pivoting towards or away from the axis established by the spindle 8.

It is therefore a first requirement of my invention that each of the cutting members be pivotally carried through a plane substantially inclusive of the axis of rotation of the supporting means.

Consideration is again directed to the fact that the same principle is involved whether the arms are pivoting either towards or away from the spindle 8, as in both instances, it is necessary for a knife to lag behind the carrier 4. If, however, an attempt is made to treat a surface that would require a knife to move both nearer to and further away from the spindle 8, it will be found that it is impossible to remove the entire surface layer accurately. This follows because the pivoting of the arm carrying the knife further away from the spindle 8, for example, carries a retarded advancement of the knife relative to the carrier 4, and if it is necessary for the knife to move to a point substantially closer to the spindle 8 its movement towards that point will require a movement of the cutting member at a rate faster than the movement of the carrier 4 with the result that portions of the surface would be skipped and untreated. This result might be in part obviated by requiring normally the removal of more than one layer from other parts of the object, but in my invention, I prefer that a uniform layer be removed. This removal of more than one layer is not regarded desirable, particularly since it is to be noted that my invention, as above described, will permit effective surface layer removal during minor irregularities in the shape of the object that may require a slight reverse movement of the knife.

For that reason, I prefer to employ a separate cutting member for each of the major trends that an object to be treated presents. For example, objects such as an apple or potato involve two major trends, that is, the middle portion being larger than the end portions. A single knife would have two major movements, one from one end to the middle zone, and the other from the middle zone to the other end. For that reason and in order to reduce the distance of travel of the carrier 4 to a minimum, I provide through the structure above described that when the carrier 4 is in one extreme position one of the cutting members is in a position substantially common to the other cutting member when the carrier 4 is in its other extreme position, as will be noted from a comparison of Figs. 1 and 3. This common position is in substantial radial alignment with the point C of the spindle head 9 and in placing the object P on the spindle 8 it is desirable that the largest portion of the object be placed substantially in radial alignment with the common point C. Actually, however, the common position of the knives involves sufficient overlap in cutting to ensure the entire removal of a surface layer from the object P.

In Fig. 1 when the knife 30 is in the common position the knife 31 is adjacent the spindle 8 so that when an object has been placed on the head 9, rotation of the crank 15 will rotate the object P and move the carrier towards the left as viewed in Fig. 1. As the carrier moves, the roller 42 advances along the cam portion 48a and the knife 30 comes in contact with rotating surface of the object P. At the same time, the knife 31 advances in fixed relation to the carrier 4 adjacent the spindle 8 until one end of the object P is encountered. Thus, the knife 30 is advancing along the object P from the largest portion

of the object towards one end, while the knife 31 is advancing from the other end towards such largest portion. By this construction it will be appreciated that the pressures of the knives 30 and 31 against the object are always favorably distributed. During this movement, both of the knives 30 and 31 may lag behind the movement of the carrier 4 as required by the size and shape of the object, it being understood that the carrier 4 has a movement greater than the arbitrarily selected maximum distance either of the knives 30 and 31 may travel.

Referring now to Fig. 7 it will be apparent that the carrier has advanced from the position shown in Fig. 1. It will be seen that the knives have advanced along the surface of the object P. In their dotted line position in Fig. 7 it will be seen that removal of the surface layer from the object is substantially complete, although the carrier is not in the other extreme position shown in Fig. 3. As soon as a knife has completed its cutting it moves either in fixed relation to the carrier 4 or away from the object P towards an inoperative position as determined by the particular object being treated. For example, the knife 30 in its dotted line position in Fig. 7 will be prevented by its stop 45 from pivoting inwardly beyond the axis of the spindle 8 and thereafter it will move in fixed relation to the carrier 4 until the trip 50 becomes effective. As soon as the knife 31 reaches the common position, the roller 44 on its arm 35 will come in contact with the cam portion 49^a and further movement will carry the cutting member 31 into the inoperative position shown in Fig. 3 so that since both knives 30 and 31 are in an inoperative position the object P may be removed safely and easily from the spindle 8 and replaced.

The operation of my device may then be continued, that is, another object may be treated during movement of the carrier 4 from the position shown in Fig. 3 to the position shown in Fig. 1. However, for convenience it may now be assumed that no object is on the spindle 8, thus when the crank is turned, the carrier 4 advances permitting the springs 39 to pivot the arms 34 and 35 inwardly. It will be appreciated that the stops 45 and 46 limit the inward pivoting of the arms 34 and 35 but attention is directed to the cam portions 48^b and 49^b which pivot the arms 34 and 35 to maintain the cutting members or knives 30 and 31 out of contact with the spindle head 9.

During the removal of the surface layers from such objects as the object P, it will be appreciated that since the knives are universally mounted on the arms 34 and 35 they are free to adjust themselves into proper cutting positions as required by the portion of the object to be treated.

With the disclosure of my invention as above set forth, certain other factors should be considered. As above stated, and as will be obvious, the number of knives employed may be one or more in the surface treatment of that portion of an object presenting a major trend, i. e., a portion which is either increasing or decreasing in size.

As far as the general construction of my invention is concerned, any means may be employed to effect the desired relative movement of the object and of the cutting means. That is to say, in accordance with my invention, it is necessary to have relative rotation between the object and the cutting means and relative linear motion between the object and the cutting means. Because such a device must be durable, efficient and eco-

nomical to manufacture, the relative motions between the object and the cutting means may be most readily effected in accordance with the structure that I have shown and described.

5. What I therefore claim and desire to secure by Letters Patent is:

1. Paring apparatus or the like comprising rotatable object supporting means, a reciprocable carrier, means for simultaneously rotating said supporting means, and advancing said carrier in predetermined relation, a cutting member effective to remove a surface layer from the object as it rotates, and means connecting said cutting member to said carrier, said connecting means including a pivot, said connecting means supporting said cutting member for arcuate movement in a plane substantially inclusive of the axis of the rotated object to cause a retarded advancement of said cutting member relative to said carrier whenever the path of said cutting member varies in relation to the path of said carrier to permit said cutting member to advance along said object at a substantially constant rate, the position of said pivot being at a greater radial distance from the axis of said supporting means than the radius of the largest object to be treated.

2. Paring apparatus or the like comprising rotatable object supporting means, a carrier, means for simultaneously rotating said supporting means and advancing said carrier in predetermined relation, a cutting member effective to remove a surface layer from the object as it rotates, and means connecting said cutting member to said carrier to cause a retarded advancement of said cutting member relative to said carrier whenever the path of said cutting member varies in relation to the travel of said carrier, said connecting means comprising a spring controlled arm pivotally connected to said carrier so that said cutting member may travel arcuately in a plane substantially inclusive of the axis of said supporting means, and a universal joint connecting said cutting member to said arm so that said cutting member may adjust itself to the surface of the supported object.

3. Paring apparatus or the like comprising rotatable object supporting means, a reciprocable carrier, means for rotating said supporting means and advancing said carrier in predetermined relation, a cutting member, means connecting said cutting member to said carrier to cause a retarded advancement of said cutting member relative to said carrier, said connecting means comprising an arm pivotally mounted on said carrier to support said cutting member in a plane substantially inclusive of the axis of rotation of said supporting means, the position of the pivoting of said arm being at a greater radial distance from the axis of said supporting means than the radius of the largest object to be pared, and resilient means in control of said arm urging said cutting member towards said axis.

4. Paring apparatus or the like comprising rotatable object supporting means, a reciprocable carrier, means for rotating said supporting means and reciprocating said carrier in predetermined relation, a cutting member, means connecting said cutting member to said carrier to cause a retarded advancement of said cutting member relative to said carrier, said connecting means comprising a cutting member supporting arm pivotally mounted on said carrier for movement in a plane substantially inclusive of the axis of rotation of said object supporting means, the point of pivoting of said arm being at a greater

radial distance from the axis of said supporting means than the radius of the largest object to be pared, and resilient means in control of said arm urging said cutting member towards said axis, and means to limit the inward movement of said arm to prevent its contact with said supporting means.

5. Paring apparatus or the like comprising rotatable object supporting means including a spindle having a head, a reciprocable carrier, means for rotating said supporting means and reciprocating said carrier in predetermined relation, a cutting member, means connecting said cutting member to said carrier to cause a retarded advancement of said cutting member relative to said carrier, said connecting means comprising an arm pivotally mounted on said carrier to support said cutting member in a plane substantially inclusive of the axis of rotation of said supporting means, resilient means in control of said arm urging said cutting member towards said axis, and means to control the movement of said arm when under the influence of said resilient means to carry said cutting member in desired relation to the axis of said supporting means and away from said spindle to avoid said head as said carrier is moved from one extreme position to the other extreme position.

6. Apparatus for removing a surface layer from an object, said apparatus comprising object supporting means constituting an axis, cutting means, supporting means for said cutting means, means to rotate one of said supporting means about said axis and to effect advancement of the other of said supporting means relative thereto in predetermined relation to the rotation of said rotated supporting means, said cutting means including a pivotal connection with said second named supporting means at a greater radial distance from said axis than the radius of the largest object to be pared, and said cutting means being effective as the distance of the portion of the object being treated varies in relation to said axis to cause the relative advancement of said cutting means and said object to remain substantially constant, the plane of movement of said cutting means being substantially inclusive of said axis.

7. Paring apparatus comprising rotatable object supporting means having a predetermined portion selected to establish a radial zone to include the largest portion of the object, a reciprocable carrier, means to reciprocate said carrier and to rotate said supporting means in predetermined relation, a pair of cutting members, an arm for each of said cutting members pivotally mounted on said carrier to support its cutting member in a plane substantially inclusive of the axis of rotation of said supporting means, resilient means in control of each arm to urge said arms towards each other and towards said axis, the length of said arms and the distances of travel of said carrier being determined by the maximum size of objects to be treated and the relation of the maximum and minimum distances of the surfaces to be treated with said axis and being inter-related so that at extreme positions of said carrier, said cutting members are alternately carried through said radial zone when said arms are pivoted against the action of said resilient means into an inoperative position, and means to carry each of said cutting members into an inoperative position whenever it reaches said common zone, the other of said cutting members being carried by said resilient means towards said

axis and away from said object as said carrier approaches an extreme position.

8. Paring apparatus comprising rotatable object supporting means having a predetermined portion selected to establish a radial zone to include the largest portion of the object, a reciprocable carrier, means to reciprocate said carrier and to rotate said supporting means in predetermined relation, a pair of cutting members, an arm for each of said cutting members pivotally mounted on said carrier to support its cutting member in a plane substantially inclusive of the axis of rotation of said supporting means, resilient means in control of each arm to urge said arms towards each other and towards said axis, the length of said arms and the distances of travel of said carrier being determined by the maximum size of objects to be treated and the relation of the maximum and minimum distances of the surfaces to be treated with said axis and being inter-related so that at extreme positions of said carrier, said cutting members are alternately carried through said radial zone when said arms are pivoted against the action of said resilient means into an inoperative position, means to carry each of said cutting members into an inoperative position whenever it reaches said common zone the other of said cutting members being carried by said resilient means towards said axis and away from said object when said carrier is in one extreme position, and means in control of one of said arms when said carrier is in the other extreme position to carry it from adjacent said axis to an inoperative position.

9. Paring apparatus comprising rotatable object supporting means, reciprocable carrier means, means to reciprocate said carrier means and to rotate said supporting means in predetermined relation, a pair of cutting members, and means connecting said cutting members to said carrier to cause a retarded advancement of said cutting members relative to said carrier on changes in shape of a supported object, said connecting means comprising an arm for each of said cutting members pivotally mounted on said carrier means to support its cutting member in a plane substantially inclusive of the axis of rotation of said supporting means, and resilient means in control of each arm to urge said arms toward each other and towards said axis, and means to control said arms so that when said carrier means are in either extreme position one of said cutting members is in an inoperative position relatively remote from said object and said axis, and the other of said cutting members is in an inoperative position.

10. Paring apparatus comprising rotatable object supporting means having a predetermined portion selected to establish a radial zone to include the largest portion of a supported object, reciprocable carrier means, means to reciprocate said carrier means and to rotate said supporting means in predetermined relation, a pair of cutting members, and means connecting said cutting members to said carrier means to permit a retarded advancement of said cutting members relative to said carrier on changes in shape of a supported object, said connecting means comprising an arm for each of said cutting members pivotally mounted on said carrier means to support its cutting member in a plane substantially inclusive of the axis of rotation of said supporting means, and resilient means in control of each arm to urge said arms towards each other and towards said axis, and means to control said arms

so that when said carrier means are in either extreme position one of said cutting members is in an inoperative position relatively remote from said object and said axis and in said radial zone, and the other of said cutting members is in an inoperative position.

11. Paring apparatus comprising rotatable object supporting means comprising a spindle including an object piercing head having a predetermined portion selected to establish a radial zone to include the largest portion of a supported object, reciprocable carrier means, means to reciprocate said carrier means and to rotate said supporting means in predetermined relation, a pair of cutting members, and means connecting said cutting members to said carrier means to permit a retarded advancement of said cutting members relative to said carrier on changes in shape of a supported object, said connecting means comprising an arm for each of said cutting members pivotally mounted on said carrier means to support its cutting member in a plane substantially inclusive of the axis of rotation of said supporting means, and resilient means in control of each arm to urge said arms towards each other and towards said axis, and means to control said arms so that when said carrier means are in either extreme position one of said cutting members is in an inoperative position relatively remote from said object and said axis and in said radial zone and when said carrier means are in one extreme position the other of said cutting members is in an inoperative position relatively remote from said object but adjacent said spindle, and when said carrier means are in the other extreme position, the other of said cutting members is in an inoperative position relatively remote from said object and said axis to facilitate access to said supporting means.

12. Paring apparatus comprising rotatable object supporting means comprising a spindle including an object piercing head having a predetermined portion selected to establish a radial zone to include the largest portion of a supported object, reciprocable carrier means, means to reciprocate said carrier means and to rotate said supporting means in predetermined relation, a pair of cutting members, and means connecting said cutting members to said carrier means to cause a retarded advancement of said cutting members relative to said carrier on changes in shape of a supported object, said connecting means comprising an arm for each of said cutting members pivotally mounted on said carrier, means to support its cutting member in a plane substantially inclusive of the axis of rotation of said supporting means, and resilient means in control of each arm to urge said arms towards each other and towards said axis, and means to control said arms so that when said carrier means are in either extreme position one of said cutting members is in an inoperative position relatively remote from said object and said axis and when said carrier means are in one extreme position the other of said cutting members is in an inoperative position relatively remote from said object but adjacent said spindle, and when said carrier means are in the other extreme position, the other of said cutting members is in an inoperative position relatively remote from said object and said axis to facilitate access to said supporting means, and manually operable means to dislodge an object from said spindle.

13. Paring apparatus comprising rotatable ob-

ject supporting means having a predetermined portion selected to establish a radial zone to include the largest portion of a supported object, reciprocable carrier means, means to reciprocate said carrier means and to rotate said supporting means in predetermined relation, a pair of cutting members, and means connecting said cutting members to said carrier means to cause a retarded advancement of said cutting members relative to said carrier on changes in shape of a supported object, said connecting means comprising an arm for each of said cutting members pivotally mounted on said carrier means to support its cutting member in a plane substantially inclusive of the axis of rotation of said supporting means, and resilient means in control of each arm to urge said arms towards each other and towards said axis, means to limit the inward pivoting of said arms by said resilient means to maintain said cutting members in desired relation to said axis and out of contact with said supporting means, and means to control said arms so that when said carrier means are in either extreme position one of said cutting members is in an inoperative position relatively remote from said object and said axis and in said radial zone and the other of said cutting members is in an inoperative position relatively remote from said object but adjacent said axis.

14. Paring apparatus comprising rotatable object supporting means comprising a spindle having an object piercing head, having a predetermined portion selected to establish a radial zone to include the largest portion of a supported object, reciprocable carrier means, means to reciprocate said carrier means and to rotate said supporting means in predetermined relation, a pair of cutting members, and means connecting said cutting members to said carrier means to permit a retarded advancement of said cutting members relative to said carrier on changes in shape of a supported object, said connecting means comprising an arm for each of said cutting members pivotally mounted on said carrier means to support its cutting member in a plane substantially inclusive of the axis of rotation of said supporting means, and resilient means in control of each arm to urge said arms towards each other and towards said axis, means to limit the inward pivoting of said arms by said resilient means to maintain said cutting members in desired relation to said axis and out of contact with said spindle and said head, and means to control said arms so that when said carrier means are in either extreme position one of said cutting members is in an inoperative position relatively remote from said object and said axis and in said radial zone, and the other of said cutting members is in an inoperative position relatively remote from said object but adjacent said axis.

15. Apparatus for removing a surface layer from an object, said apparatus comprising a frame, rotatable object supporting means supported by said frame and including a gear, cutting means, a carrier for said cutting means slidably supported by said frame, an arm pivotally connected to said carrier, an elongated driven gear rigidly mounted on said arm, driving means including a gear in mesh with each of said driven gears to rotate said supporting means and to reciprocate said carrier in predetermined relation, means to maintain said last named gear in mesh with its driving gear to carry said driven gear around its driving gear, said last named means including a pair of vertically spaced guides, a pair

of longitudinally spaced semi-circular guides, a member on said arm, and a member on said elongated gear, said members being engageable with said guides.

16. Paring apparatus comprising a frame, rotatable object supporting means carried by said frame and having a predetermined portion selected to establish a radial zone to include the largest portion of a supported object, reciprocable carrier means slidably mounted in said frame, means to reciprocate said carrier means and to rotate said supporting means in predetermined relation, a pair of cutting members, and means connecting said cutting members to said carrier means to cause a retarded advancement of said cutting members relative to said carrier, said connecting means comprising an arm for each of said cutting members pivotally mounted on said carrier means to support its cutting member in a plane substantially inclusive of the axis of rotation of said supporting means, and resilient means in control of each arm to urge said arms towards each other and towards said axis, and means to control said arms so that when said carrier means are in either extreme position one of said cutting members is in an inoperative position relatively remote from said object and said axis and in said radial zone and the other of said cutting members is in an inoperative position, said controlling means comprising a member on each arm, and a cam for each of said members, one of said cams being disposed on said frame to be engaged by one of said arm members when said carrier means are in one extreme position and the other of said cams being disposed on said frame to be engaged by the other of said arm members when said carrier means are in the other extreme position.

17. Paring apparatus comprising a frame, rotatable object supporting means carried by said frame, said supporting means comprising a spindle having a head having a predetermined portion selected to establish a radial zone to include the largest portion of a supported object, reciprocable carrier means slidably mounted in said frame, means to reciprocate said carrier means and to rotate said supporting means in predetermined relation, a pair of cutting members, and means connecting said cutting members to said carrier means to cause a retarded advancement of said cutting members relative to said carrier, said connecting means comprising an arm for each of said cutting members pivotally mounted on said carrier means to support its cutting member in a plane substantially inclusive of the axis of rotation of said supporting means, and resilient means in control of each arm to urge said arms towards each other and towards said axis, and means to control said arms so that when said carrier means are in either extreme position one of said cutting members is in an inoperative position relatively remote from said object and said axis and in said radial zone and the other of said cutting members is in an inoperative position, said controlling means comprising a member on each arm, and a cam for each of said arm members, said cams being disposed on said frame to be engaged by said arm members when either of said cutting members approaches said head and being adapted to be fully effective when the carrier means are in either extreme position.

18. Paring apparatus comprising rotatable object supporting means having a predetermined

portion selected to establish a radial zone to include the largest portion of a supported object, reciprocable carrier means to reciprocate said carrier means and to rotate said supporting means in predetermined relation, a pair of cutting members, and means connecting said cutting members to said carrier means to cause a retarded advancement of said cutting members relative to said carrier on changes in shape of a supported object, said connecting means comprising an arm for each of said cutting members pivotally mounted on said carrier, means to support its cutting member in a plane substantially inclusive of the axis of rotation of said supporting means, each of said cutting members being mounted on its arm for limited universal movement, and resilient means in control of each arm to urge said arms towards each other and towards said axis, and means to control said arms so that when said carrier is in either extreme position one of said cutting members is in an inoperative position relatively remote from said object and said axis and in said radial zone and the other of said cutting members is in an inoperative position.

19. Paring apparatus comprising rotatable object supporting means having a predetermined portion selected to establish a radial zone to include the largest portion of a supported object, reciprocable carrier means to reciprocate said carrier means and to rotate said supporting means in predetermined relation, a pair of cutting members, and means connecting said cutting members to said carrier, means to cause a retarded advancement of said cutting members relative to said carrier, said connecting means comprising an arm for each of said cutting members pivotally mounted on said carrier means to support its cutting member in a plane substantially inclusive of the axis of rotation of said supporting means, each of said cutting members being mounted on its arm for limited universal movement and guide means for each of said cutting members to adjust said cutting member into proper cutting position, said guide means being effective on changes in shape of the object on movement of said carrier means and on rotation of said object, and resilient means in control of each arm to urge said arms towards each other and towards said axis, and means to control said arms so that when said carrier is in either extreme position one of said cutting members is in an inoperative position relatively remote from said object and said axis and in said radial zone and the other of said cutting members is in an inoperative position.

20. Paring apparatus comprising a rotatable object supporting means having a predetermined portion selected to establish a radial zone to include the largest portion of a supported object, cutting means, supporting means for said cutting means, means to rotate said object supporting means and to reciprocate one of said supporting means to effect relative movement between said cutting means and a rotating supported object, said cutting means comprising a pair of cutting members, an arm for each of said cutting members, each of said arms being pivotally connected to the second-named supporting means so that as the reciprocated supporting means approaches either end of its travel one of said cutting members occupies said radial zone and the other of said cutting means is adjacent the axis of said rotatable object supporting means, and means to position inopera-

tively each of said cutting members remote from the object when it occupies said radial zone and when said reciprocated supporting means is at either extreme position.

21. Paring apparatus comprising a rotatable object supporting means having a predetermined portion selected to establish a radial zone to include the largest portion of a supported object, cutting means, supporting means for said cutting means, means to rotate said object supporting means and to reciprocate one of said supporting means to effect relative movement between said cutting means and a rotating supported object, said cutting means comprising a pair of cutting members, an arm for each of said cutting members, each of said arms being pivotally connected to the second-named supporting means so that as the reciprocated supporting means approaches either end of its travel one of said cutting members occupies said radial zone and the other of said cutting means is adjacent the axis of said rotatable object supporting means, means to position inoperatively each of said cutting members remote from the object when it occupies said radial zone and when said reciprocated supporting means is at either extreme position, and means to position inoperatively the other of said cutting means remote from said axis when said reciprocated supporting means is in one extreme position.

22. An apparatus for removing a surface layer from an object, an arm, a knife having a bowed cutting edge comprising a central part and curved end parts, means including a pivot to connect said knife to said arm, the central part of said knife being at a lesser distance from said pivot than the end parts so that said knife while effective to remove parings when either one of the end parts is in contact with the object tends to return to a normal balanced position in which said central part only is in contact with the object.

23. An apparatus for removing a surface layer from an object, an arm, a knife having a bowed

cutting edge, means including a pivot to connect said knife to said arm, the central part of said knife being at a lesser distance from said pivot than the end parts so that said knife while effective to remove parings when either one of the end parts is in contact with the object tends to return to a normal balanced position in which said central part only is in contact with the object.

24. Paring apparatus or the like comprising rotatable object supporting means, a reciprocable carrier, means for simultaneously rotating said supporting means and reciprocating said carrier in predetermined relation, a cutting member effective to remove a surface layer from the object as it rotates, spring controlled means pivotally connecting said cutting member to said carrier to cause arcuate travel of said cutting member in a plane substantially inclusive of the axis of said rotated object, and means actuated on a predetermined movement of said carrier in at least one direction to pivot said connecting means to carry said cutting member into an inoperative position.

25. Paring apparatus or the like comprising rotatable object supporting means, a carrier, means for simultaneously rotating said supporting means and effecting relative reciprocating movement between said carrier and said supporting means, cutting members, spring controlled means pivotally connecting each of said cutting members to said carrier to cause arcuate travel of said cutting member in a plane substantially inclusive of the axis of said rotated object, said cutting members being spaced from each other to contact different portions of said object, and means actuated on a predetermined movement of said carrier to pivot said connecting means to carry one of said cutting members into an inoperative position when said cutting member reaches the portion of said object treated by another of said cutting members.

CORNELIUS VERNON McCUALEY.
